UNITED STATES PATENT OFFICE.

EDWARD F. BURKE, OF PHILADELPHIA, PENNSYLVANIA, ASSIGNOR OF ONE-HALF TO
LOUIS BLACK, OF PHILADELPHIA, PENNSYLVANIA.

BUTTON-SEWING MACHINE.

1,120,274.

Specification of Letters Patent.

Patented Dec. 8, 1914.

Application filed August 24, 1912. Serial No. 716,796.

To all whom it may concern:

Be it known that I, EDWARD F. BURKE, a citizen of the United States, residing at Philadelphia, in the county of Philadelphia and State of Pennsylvania, have invented certain new and useful Improvements in Button-Sewing Machines, of which the following is a specification.

My invention relates to improvements in button sewing machines, an object of the invention being to provide an improved construction of oscillator in combination with a rotary looper located within the oscillator and between which and the button, an improved thread breaking arm is adapted to be moved.

A further object is to provide an improved arrangement of button holding jaws, in combination with an improved cylindrical oscillator, and a rotary looper within the oscillator together with an improved thread breaking arm which is movable through the oscillator and against the thread as the button holding jaws are elevated to maintain the thread taut, so that it is easily broken.

A further object is to provide a button sewing machine with improved mechanism for controlling the number of stitches which automatically stops the machine after a pre-determined number of stitches have been made through the button, said means capable of being varied by the substitution of one worm wheel for another or the re-arrangement of fingers on the worm wheel, so that any desired number of stitches may be had.

A further object is to provide a button sewing machine with improved thread breaking means which leaves through the needle, a length of thread sufficient to insure the proper operation of sewing the next button.

A further object is to provide a button sewing machine which will occupy but small space, which will be strong and durable in construction, and which will most efficiently perform the functions for which it is intended.

With these and other objects in view, the invention consists in certain novel features of construction and combinations and arrangements of parts as will be more fully hereinafter described and pointed out in the claims.

55 In the accompanying drawings: Figure 1

is a view in side elevation with the side plate removed illustrating my improved mechanism contained within the casing. Fig. 2 is a view in elevation of the opposite side of my improved button sewing machine. Fig. 3 is a 60 view in vertical section on the line 3—3 of Fig. 1. Fig. 4 is a view in horizontal section on the line 4—4 of Fig. 1. Fig. 5 is a view in elevation. Fig. 6 is a view in rear elevation. Fig. 7 is a view in horizontal section 65 on the line 7—7 of Fig. 1. Fig. 8 is a fragmentary view in vertical section on the line 8—8 of Fig. 7. Fig. 9 is a fragmentary view in vertical section on the line 9—9 of Fig. 7 with parts of the mechanism removed 70 for clearness in illustrating other parts. Fig. 10 is a front end view of the oscillating cylinder, looper, and thread breaker with the cover disk removed. Fig. 11 is a view of the rear face of disk 83 showing the cam 75 groove therein. Fig. 12 is a perspective view of the rotary looper, and Fig. 13 is a view in elevation on a reduced scale showing the removable plate 6 forming one side of the casing.

1, represents a support to which the casing 2 of my improved button sewing machine is secured. The preferable means of securing the casing is to project a bolt 3 through registering openings in support 1, 85 and the base 4 of the casing, and secured by means of a nut 5 in the casing screwed onto the bolt against the base 4. This nut 5 is inclosed within the casing when a removable plate 6 is secured therein. This plate 6 is 90 provided with dowels 7 to fit in corresponding sockets 7^a in base 4, and is provided at its upper end with a lock 8 adapted to project its locking bolt into a recess 9 in the top of the casing, so that the mechanism 95 inclosed within the casing will be securely locked and protected from unauthorized persons.

The casing is of angular formation, its upper portion at the front extending outwardly forming a rectangular overhang 10 through which the needle bar 11 is mounted to reciprocate. A needle 12 is secured in the lower end of the needle bar by means of a screw 13, and the upper end of the needle bar is provided with an opening 14 through which the thread 15 is passed. This thread 15 is also projected through the eye of needle 12, and is fed to the needle bar by means of a friction pulley 16, the supply 110

spool of the thread being supported in any approved manner (not shown).

The needle 12 is adapted to reciprocate between button holding jaws 17, and through a transverse slot 18 in the upper face of my improved cylindrical oscillator 19. The cylindrical oscillator 19 is supported upon a tubular journal 20 having a flanged end 21 fixed to the front face of casing 2 by means of screws 22. Journal 20 is appreciably shorter than the cylindrical oscillator, so that a chamber is formed in the outer end of the oscillator in which my improved rotary looper 23 is adapted to revolve. This looper is inclosed within its chamber by means of a hinged disk 24 on the end of the oscillator, and is provided with an angular shank 25 which is projected into an angular opening 26 in the end of the main drive shaft 27. This shaft 27 is positioned horizontally and extends through the tubular journal 20 and through an opening 28 in the rear end of the casing.

A spacing collar 29 is secured on the shaft 27 and controls the longitudinal movement thereof. On the rear end of shaft 27, fast and loose pulleys 30 and 31 respectively are mounted, and a belt 32 connected with any suitable source of power is shifted from one pulley to the other by means of a belt shifter 33. This belt shifter 33 has an eye 34 at its free end through which the belt 32 passes, and at its other end is secured to one end of an angular arm 35. This arm 35 at its inner end is pivotally supported upon a screw 36 secured in the casing wall, and a spring 37 is positioned around the screw and bears against the arm exerting a downward pressure upon the same. The free end of this arm 35 extends through a slot 38 in the rear end wall of casing 2, and to this arm outside of the casing, the belt shifter 33 is secured. On the extreme end of the arm 35, a finger 39 is formed. This finger extends downwardly and is normally elevated above the periphery of a crank disk 40. This crank disk 40 preferably forms an integral part of the fast pulley 30, but is larger in diameter and its outer surface is cam shaped with a recess 41 therein, one wall of which constitutes a shoulder 42. In this wall or shoulder 42, a recess is provided for the reception of a coiled spring 43. This spring 43 constitutes a buffer and is adapted to engage the finger 39 when the arm 35 is in its lowest position. In other words, the arm 35 is normally elevated permitting the disk to freely revolve. At a pre-determined time, as will be hereinafter explained, this arm is permitted to fall so that the finger 39 will lie in the path of shoulder 42 to stop the mechanism, and the force of contact is cushioned by means of the spring 43.

The arm 35 is held in its elevated position by means of a trip 44. This trip 44 is ful-

crumed between its ends on a screw 45 screwed into the end wall of casing 2, and is provided with a spring 46 which tends to move its lower hooked end 46a under arm 35. The arm 35 is elevated to this position by means of a lever 47 fulcrumed between its ends on a bracket 48 on the bottom of support 1. This lever 47 may be made of heavy wire and connected at one end by a screw 49 with an upright plunger 50. This plunger 50 is guided in the casing and as shown in dotted lines in Fig. 9, is located in position to elevate the arm when moved upwardly. The other end of lever 47 is connected by a link 51 with any suitable operating means (not shown). Such operating means usually consists of a treadle, but may of course be varied.

The trip 44 is moved by fingers 52 on the outer face of a worm wheel 53. This worm wheel 53 is journaled on a screw 54 secured in an enlargement 55 on the inner face of the casing, and these fingers 52 are movable through a path which brings them in contact with a beveled lug 56 on the upper end of the trip. The number of these fingers 52 may be varied in accordance with the number of stitches to be given each button, as it is to be understood that each finger operates the trip. In the construction shown, the trip will be operated three times during each complete revolution of the worm wheel. The worm wheel 53 is driven by a worm 57 fixed to a vertical shaft 58 mounted in bearings 59 and 60 in the casing. This shaft 58 is provided on its lower end with a beveled gear 61 which meshes with a beveled gear 62 on drive shaft 27, so that direct power is transmitted from shaft 27 to shaft 58.

In the upper portion of casing 2, a horizontally positioned rocker shaft 63 is mounted and this rocker shaft is provided with a rocker arm 64 which is adjustably connected by a rod 65 with a clamp 66 on needle bar 11. Motion is transmitted to this rocker shaft 63 by means of the crank disk 40, said crank disk 40 having a crank pin or screw 67 which is connected by a link 68 with an arm 69 on rocker shaft 63, whereby a rotary motion of crank disk 40 imparts a rocking or oscillating movement to the rocker shaft 63.

To one side of the cylindrical oscillator 19, an arm 70 is fixed and projects through a curved slot 71 in the front end of casing 2. This arm 70 at its inner end is pivotally connected by a screw 72 with the lower end of a link 73 located outside of the casing. The upper end of this link is connected by a bolt 74 and a wing nut 75 with an oscillating arm 76. This arm 76 has a channel therein formed by inwardly projecting flanges 77 so that a guide is provided for the head of bolt 74, and a washer 78 is preferably interposed

between the nut 75 and the flanges 77. This arm 76 as above stated, is an oscillating arm, and at one end is pivotally connected by a pin 79 with the casing 2.

Arm 76 is provided on its inner face with a pin 80 which projects through a slot 81 in casing 2, and is mounted in a cam groove 82 in a disk 83. This disk 83 is fixed to the back of a large beveled gear 84 mounted inside of the casing upon a screw 85 screwed into the wall of the casing and constituting a fixed journal upon which the gear 84 revolves. This gear 84 meshes with a beveled pinion 86 secured to shaft 58, so that the rotary movement of gear 84 and disk 83 imparts an oscillating movement to the cylindrical oscillator 19.

The button gripping jaws 17 above referred to are of bowed form, and at their inner ends are pivotally connected to the lower face of a bar 87 by means of screws 88. These jaws are connected by two pivoted links 89, and the center pivot 90 connecting the links 89 is secured to a plunger 91. This plunger 91 extends into a recess 92 in bar 87, and a coiled spring 93 in said recess exerts outward pressure on the plunger tending to draw the jaws 17 toward each other.

The inward movement of the jaws may be adjusted by set screws 94 which are projected through lugs 95 on the jaws 17. These screws 94 bear against the side faces of bar 87 and act as stops to limit the pivotal movement of the jaws by means of the spring. The opposite faces of said jaws, at their free ends, are grooved as shown at 96 to receive the button illustrated in dotted lines in Fig. 7, said button being of the two hole type.

The bar 87 is pivotally supported near its inner end on a pin 97 which extends through perforated ears 98 on the upper face of cylinder 19. The shorter end of this bar 87 projects through a slot 99 in the front wall of the casing, and on its inner end is provided with a hook 100 which is connected by a coiled spring 101 with a screw 102 secured inside the casing. The shorter end of this bar 87 is adapted to be engaged by an arm 103 fixed to a rod 104. This rod 104 is supported to slide vertically in bearings 105 on the side wall of casing 2, and is connected by a link 106 with any suitable treadle mechanism (not shown).

The upper end of the rod 104 is bent in inverted U-shape as indicated at 107, and at its free end extends through an opening 108 in the top of the casing 2. A coiled spring 109, located around rod 104 and between the upper bearing 105 and a collar 110 on the rod, exerts upward pressure on the rod to normally hold it in the elevated position indicated. The inverted U-shaped upper end 107 of this rod 104 extends across the thread 15, so that when the rod is drawn

downwardly, it causes a bight in the thread between the needle bar 11 and the friction pulley 16 for a purpose which will herein-after appear.

A relatively short arm 111 is fixed to the rod 104 and when said rod is moved downwardly, this arm 111 is adapted to strike a crank arm 112 on a shaft 113 of a thread severing device which is supported in a block 114 secured to the under face of cylinder 19. The thread severing device comprises the shaft 113, crank arm 112, and a hook shaped thread breaker proper 115 which is preferably formed by bending the end of the shaft 113 and which is movable through slots 116 in cylinder 19. The free end of this thread breaker is provided with a groove 117 which is adapted to receive and hold the thread when the thread breaker is moved across the path of the needle between the same and the looper 23. The thread breaker is normally held in the position indicated by means of a spring 121 which is secured to a screw 122 on one side of block 114, the free end of said spring engaging the arm 112 and exerting upward pressure thereon. The looper 23 as seen most clearly in Fig. 12 is provided with a hooked end 118 and a cam end 119, which are located at an angle of approximately 135°. At the junction of the hooked end 118 and the cam end 119, an opening 120 is provided through which the needle 12 reciprocates.

The operation is as follows: Assuming a button to be in position between the jaws 17 and the goods upon which the button is to be sewed located under the jaws 17 and on top of the cylindrical oscillator 19, the operator exerts a downward pull upon link 51. The downward movement of link 51 through the medium of lever 47 and plunger 50 elevates arm 35 to a position where it is caught by the lower hooked end 46a of trip 44. This movement of arm 35 causes the finger 39 to be moved out of the path of shoulder 42 and at the same time causes the belt shifter 33 to slide the belt 32 onto the fast pulley 30. Motion is then transmitted directly to shaft 27 and through the medium of the several mechanisms above described, shaft 63 is rocked and cylinder 19 oscillated. This oscillating movement of the cylinder 19 is intermittent. In other words, it is oscillated in one direction and remains stationary for a pre-determined length of time and then is oscillated in the other direction and remain stationary for a pre-determined length of time. This movement is controlled by the shape of cam groove 82 in disk 83, and causes the button to be shifted to present first one hole of the button to the needle and thread, and then the other. The looper 23 is continuously revolving so that the thread as it is carried through the opening 120 is caught by the

hooked end 118 and looped. The cam 119 moves the looped end out of the path of the needle and the upward movement of the needle with the thread causes the thread to form a chain stitch against the under face of the goods to which the button is being sewed. The number of stitches is regulated by the fingers 52 on worm wheel 53. When this worm wheel is moved a pre-determined distance, one of its fingers 52 will engage the upper end of trip 44 moving the trip and causing it to release arm 35. Arm 35 then falls with its finger 39 upon the periphery of crank disk 40. When the shoulder 42 or rather the spring 43 in said shoulder comes in contact with the finger 39, the machine will be stopped, the spring serving to cushion the contact. The operator then exerts a downward pull on link 106. This movement of link 106 causes the rod 104 to be drawn downwardly. Arm 103 strikes the shorter end of bar 87, and arm 111 engages crank arm 112, causing the thread breaker 115 to move transversely through the cylinder 19. These parts are so arranged that as the grooved end of the thread breaker 115 engages the thread, the bar 87 is moved on its fulcrum to elevate the jaws 17. This causes the thread to be drawn taut, so that the transverse movement of the thread breaker across the taut thread cleanly breaks the thread. At the same time, the downward movement of rod 104, by reason of the fact that its inverted U-shaped upper end 107 extends over the thread between the needle bar 11 and the friction pulley 16, causes a slack in the thread sufficient to allow the goods to be moved and draw a part of the thread through the eye of the needle. This is just sufficient to prevent drawing the thread entirely out of the needle and allowing a sufficient end to begin the operation of sewing the next button. It will thus be seen that by reason of the tripping mechanism above described, each button will receive the exact same number of stitches and the number of stitches is controlled by the position of the fingers 52 on worm wheel 53. These positions may be varied in accordance with the work to be done.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. A thread breaker for sewing machines comprising button holding and elevating means, a looper below the button holding means, a needle adapted to be moved

through the button in the holder, and position the thread for engagement by the looper, means for elevating the button holding means to raise the button and draw the thread taut between the button and the looper, an arm movable against the taut thread between the button and the looper to break the thread, said arm movable by the same means which elevates the button holding means, substantially as described.

2. A thread breaker for sewing machines comprising button holding and elevating means, a looper below the button holding means, a needle adapted to be moved through the button in the holder, and position the thread for engagement by the looper, means for elevating the button holding means to raise the button and draw the thread taut between the button and the looper, an arm movable against the taut thread between the button and the looper to break the thread, said arm movable by the same means which elevates the button holding means, and said arm having a thread receiving groove in its free end, substantially as described.

3. A thread breaker for sewing machines, comprising button holding and elevating means, a looper below the button holding means, a needle adapted to be moved through the button in the holder, and position the thread for engagement by the looper, means for elevating the button holding means to raise the button and draw the thread taut between the button and the looper, an arm movable against the taut thread between the button and the looper to break the thread, said arm movable by the same means which elevates the button holding means, and manually controlled operating means for moving said arm, substantially as described.

4. A thread breaker for sewing machines comprising button holding and elevating means, a looper below the button holding means, a needle adapted to be moved through the button in the holder, and position the thread for engagement by the looper, means for elevating the button holding means to raise the button and draw the thread taut between the button and the looper, an arm movable against the taut thread between the button and the looper to break the thread, said arm movable by the same means which elevates the button holding means, said arm having a thread receiving groove in its free end, and manually controlled operating means for moving said arm, substantially as described.

5. The combination with button holding and elevating means, and a looper below the button holding means, of a needle adapted to reciprocate through the button and position a thread, so that it is engaged and held by the looper, means for elevating the

button holding means and button in a direction to draw the thread taut between the button and the looper, a rotary shaft, and a curved arm connected at one end to the shaft and at its free end adapted to engage the thread between the button and the looper and break the thread when said shaft is revolved, substantially as described.

6. In a thread breaker for sewing machines, the combination of a rotary looper, vertically movable button holding and elevating means above the rotary looper, means for elevating the button holding means and button to draw the thread taut between the button and the looper, a thread breaker having a notched end to receive the thread, and means for simultaneously elevating the button holding means and moving the thread breaker across the thread to break the same between the button and the looper, substantially as described.

7. In a thread breaker for sewing machines, the combination of a rotary looper, vertically movable button holding and elevating means above the rotary looper, means for elevating the button holding means and button to draw the thread taut between the button and the looper, a thread breaker comprising a curved arm having a notched end to receive the thread, means for simultaneously elevating the button holding means and moving the thread breaker across the thread to break the same between the button and the looper, substantially as described.

8. A device of the class described comprising an oscillating casing, a looper arranged within said casing, a button holding and elevating device mounted on said casing, a needle arranged to be projected through a button in said holding device and bring a thread into operative relation with said looper, means for operating said button holding means to elevate the button and draw the thread taut between the button and the looper and a thread severing device adapted to engage and sever the thread when taut and means for operating said thread severing device, substantially as described.

9. In a device of the class described, an

oscillating casing, a looper arranged therein, the walls of said casing being slotted adjacent said looper, button holding and elevating means, a needle for projecting a thread through the button and into operative relation with said looper, means for raising the button holding means and button to draw the thread taut between the button and the looper, a thread severing device adjacent said casing and means for projecting said severing device through the slots in said casing to engage and sever the thread while taut, substantially as described.

10. In a device of the class described, an oscillating casing, a looper therein, a button holding and elevating device mounted on said casing, a thread severing device also mounted on said casing, said casing being slotted to permit said severing device to be projected thereinto, and means for simultaneously raising said button holding device and button to draw the thread taut between the button and the looper and for projecting said severing means against the thread when taut, substantially as described.

11. In a device of the class described, an oscillating casing, a looper therein, a bar pivotally mounted on said casing, button holding and elevating jaws on said bar, a needle for projecting a thread through said button into operative relation with said looper, a thread severing device pivotally mounted on said oscillating casing, an arm fixed to said thread severing device, a reciprocating member mounted adjacent said casing, means on said reciprocating member for engaging said bar to elevate the button and draw the thread taut between the same and the looper and means on said reciprocating member for engaging the arm on said severing device to project the latter against the thread when taut, substantially as described.

In testimony whereof I have signed my name to this specification in the presence of two subscribing witnesses.

EDWARD F. BURKE.
